UNITED STATES PATENT OFFICE.

HOWARD L. JOHNSTON, OF FOREST HILLS BOROUGH, PENNSYLVANIA, ASSIGNOR TO
WESTINGHOUSE ELECTRIC & MANUFACTURING COMPANY, A CORPORATION OF
PENNSYLVANIA.

FLOODLIGHT.

Application filed January 16, 1925. Serial No. 2,833.

My invention relates to lighting fixtures and particularly to a screen device for light-projecting apparatus.

It is among the objects of my invention 5 to provide a device for retaining a light-modifying screen or lens-like partition in front of the aperture of the lamp casing.

Another object of my invention is to provide a device for supporting the screen in a 10 substantial manner, but not in such rigid manner that it will be warped or broken after having been successively heated and cooled.

Devices of this character are used for flood 15 lighting. Color screens are placed in front of the light aperture for modifying the lighting effect. One form of screen heretofore used for this purpose is composed of a gelatinous or gluey substance, resembling 20 fish-glue, which contracts upon heating. Such screens are usually made of thin material that upon cooling will not spring back to its original form but the screens will rather warp or sag, even when they are held 25 loosely. Devices of this character have heretofore been provided with means for rigidly holding the screens, but the screens, after continued heating and cooling, became badly warped and finally broke.

30 My invention provides means for circulating air on both sides of the screen and means for holding the screen loosely enough to permit a slight movement thereof without undue stretching or tenting. I also provide improved means for supporting the screen and for preventing sagging or warping thereof due to heating.

In the drawings, constituting a part hereof, and in which like numerals designate like 40 parts,

Figure 1 is a front elevational view of a flood light,

Fig. 2 is a view partly in side elevation and partly in cross-section along the line 45 II-II of Fig. 1; and

Fig. 3 is a fragmentary view of the bracket showing a portion of the lamp casing and holder in cross-section.

A lamp casing 1 is mounted on a base or 50 standard 2 in any suitable manner. A screen 3 is mounted in front of the aperture 4 of the lamp casing, which may be provided with or without a lens. The holder for the screen comprises a stationary ring or flange

55 that is attached to a portion 6 of a bracket which, in turn, is clamped to a ring or bead 7 of the lamp casing 1 by means of a screw 8. An upstruck portion 9 of the bracket is disposed against the bead 7 of the lamp casing which is held rigidly between the screw 60 8 and the portion 9. Another portion 10 of the bracket extends outwardly from the lamp casing providing space between the stationary ring, and the lamp casing or lens through which air circulates and cools the 65 screen.

A hook-like extension or stop member 11 of the bracket extends around the edge of the stationary ring 5 and then inwardly in front thereof to provide a space for accom- 70 modating a movable ring 12.

Stationary ring 5 is provided with a flange 13 at its inner margin having regularly spaced openings 14 located therein, so that when wires 15 are threaded through the 75 openings, the wires are equally spaced and are parallel to each other. The movable ring 12 is provided with a similar flange 17, openings 18 and wires 19, and also with an opening 20 in the outer periphery so located that when it coincides with one of the stop members 11, the wires 15 and 19 are non-parallel.

The screen is mounted by placing it against the wires 15. The movable ring is 85 then placed in two of the stops 11 and the third stop is slipped through the opening 20 of the movable ring. The ring is then turned through an angle, preferably until the wires are at right angles to each other. 90

My invention provides a device so constituted that the screen is prevented either from sagging or from rupturing when it is heated. The opening 16 between the light 95 enclosure and the screen provides for the dissipation of a large proportion of the heat generated by the lamp, so that the screen in the first instance is protected from the direct heat of the lamp. Supporting wires are disposed on both sides of the screen 3. 100 The rings that frictionally retain the screen at the edges, are at the same time so resilient that the screen is permitted to contract slightly when unduly stretched by the effect of the heat.

105 Although I have shown and described a specific structure embodying my invention, I do not wish to be limited thereto, as modi-

ifications of my invention will suggest themselves to those skilled in the art without departing from the spirit of my invention, the scope of which is defined in the annexed claims.

I claim as my invention:

1. A lighting unit comprising a lamp enclosure, a fixed frame member, brackets secured to said enclosure for supporting said fixed frame, said brackets being bent around the edge of said frame and forming retaining fingers, a movable apertured frame having an opening in the periphery thereof, said fingers being adapted to engage the periphery of said movable frame and to release said frame when the aperture therein coincides with one of said fingers.
2. A screen device for lighting units comprising a screen for modifying the character of the projected light, an apertured stationary member for the passage of light rays, an apertured movable member coextensive with and cooperating with said stationary member for holding said screen, oppositely extending flanges forming the margin of the apertures in said members, systems of wires traversing said apertures, means in said flanges for spacing said systems of wires, brackets on said stationary member having offset members for spacing said screen from the lamp enclosure, extensions in said brackets for engaging said removable member, said removable member having means for permitting the disengagement thereof when it is rotated into a predetermined position.
3. A screen device for lighting units which comprises a screen for modifying the character of the projected light, an apertured stationary member for the passage of light rays, an apertured movable member

coextensive with and cooperating with said stationary member for frictionally retaining said screen at the outer margin thereof, oppositely extending flanges forming the margin of the apertures in said members, systems of wires traversing said apertures, means in said flanges for spacing said systems of wires, brackets on said stationary member having offset members for spacing said screen from the lamp enclosure, extensions in said brackets for engaging said removable member, said removable member having means for permitting the disengagement thereof when it is rotated into a predetermined position.

4. A screen device for lighting units which comprises a screen for modifying the character of the projected light, an apertured stationary member for the passage of light rays, an apertured movable member coextensive with and cooperating with said stationary member for holding said screen, oppositely extending flanges forming the margin of the apertures in said members, systems of wires traversing said apertures, means in said flanges for spacing said systems of wires, brackets on said stationary member having offset members for spacing said screen from the lamp enclosure, extensions in said brackets for engaging said removable member, said removable member having means for permitting the disengagement thereof when it is rotated into a predetermined position, said disengaging means being so disposed that said system of wires are non-parallel when said removable member is in the disengaging position.

In testimony whereof, I have hereunto subscribed my name this 30th day of December 1924.

HOWARD L. JOHNSTON.
